[57] CLAIM

The ornamental design for a display panel for shelving, substantially as shown and described.

DESCRIPTION

FIG. 1 is a front perspective view of a display panel for shelving showing our new design.

FIG. 2 is an elevational view taken from the end as seen from the left of FIG. 1; the opposite end being a mirror image thereof;

FIG. 3 is a front elevational view thereof;

FIG. 4 is a top plan view thereof;

FIG. 5 is a bottom plan view thereof; and

FIG. 6 is a rear elevational view thereof.

The display panel for shelving has been shown fragmentarily in FIGS. 3-6 for ease of illustration.
